UNITED STATES PATENT OFFICE.

CLARK COOPER, OF PHILADELPHIA, PENNSYLVANIA.

PNEUMATIC SIGNAL.

Application filed June 23, 1927. Serial No. 200,786.

The object of the invention is to provide improvements in fluid-actuated audible signals, and especially such as are actuated pneumatically and in multiple, either to provide increased volume or a series of musical notes to produce a harmonious chord.

There are many places and conditions in which a signal of this character is well adapted for use, but for the purpose of this 10 explanation reference will be made to the use of such signaling means upon locomotives. In the operation of railroads there are definite occasions when it is necessary for the engineer to signal from the front end 15 of a train to a conductor or other member of the crew at the rear end thereof, and in the case of freight trains across flat country the distance becomes very great, often involving a span of one hundred fifty cars, or 20 thereabouts, plus the distance that the second party may have gone back to warn an approaching train.

The usual steam whistle, besides costing several times as much to operate, sends its 25 sound waves in a general upwardly direction, even when the whistle is tilted or turned into a horizontal direction, there being no sound-directing means present. Also, when the whistle cord is pulled to full 30 open position and there is high steam pressure in the boiler, the note of the whistle becomes so high as to be practically inaudible to the human ear, even at close range and therefore so much more so at the usual distance between the ends of a train. The difference between the actual operating pressures of steam and pneumatic signals is the 35 difference roughly between a wide variation around 200 to 300 pounds in the boiler in the one case, and an easily maintained even 40 120 pounds or thereabouts in the air brake reservoir in the other case, reduced at the signal to about 60 pounds.

Having in mind these general differences 45 in the operating conditions between steam and air signals, the value of the present invention will be better understood. An object is to provide improvements in the arrangement of a series of horns or the like 50 upon a locomotive, so as to direct their respective notes unrestrained by the smoke stack and similar obstructions also carried by the locomotive, to direct their notes partly directly towards the rear of a train being 55 drawn by a locomotive equipped with the device, and to direct certain of their notes

forwardly but in such manner as to prevent the horns or the like from becoming filled with rain, snow, sleet, and dirt, due to the usual forward motion of the train, to provide for the application of air pressure to the movable parts of each signal element in a manner hereinafter described, to provide an improved connection between the several horns and their respective sound-producing 60 elements, and to provide for the mounting of the series of horn elements and their connections as a unit upon a specially designed bracket carried by a locomotive (or other vehicle), so as to permit the ready removal 65 and substitution of one unit, or any of its elements, for another such unit or corresponding elements.

With these and other objects in mind, the present invention comprises further details 70 of construction and operation which are fully brought out in the following description, when read in conjunction with the accompanying drawings, in which Fig. 1 is a perspective view of the upper forward portion of a locomotive equipped with one embodiment of the invention; Fig. 2 is a top plan view of a signal embodying the invention; Fig. 3 is a front elevation of the same; Fig. 4 is a front elevation of the improved 75 bracket and showing a signal unit of four sound-producing elements in dot-and-dash lines; and Fig. 5 is an enlarged diametrical section on the line 5—5 of Fig. 2.

Referring to the drawings, the improved 80 bracket may be mounted in any suitable manner upon a locomotive or in fact upon any other vehicle, but in the present instance is shown as comprising an angle iron, having its horizontal flange 1 fixedly secured in spaced relation above the boiler or other portion of a locomotive by means of suitable braces 2, while the other flange 3 of 85 said iron extends upwardly and has secured thereto a pair of yokes comprising central portions 4 from which extend integral angularly positioned arms 5, the outer free end portions of which arms form sockets 6, in which are normally seated the respective cylindrical portions 7 of sound-producing 90 elements (shown in Fig. 5) and normally secured in said sockets by means of collars 8.

Each element is formed of the cylinder 7 terminating in one direction in a radial flange 9, in turn merging into a cylindrical 100 flange 10, the free end portion of which is integrally connected to an enlarged cylin- 105

drical portion 11, into which leads one end of a fluid-conveying pipe 12, while the otherwise open end of said cylindrical portion 11 is spanned by a closure 13 in spaced relation 5 with a vibratory diaphragm 14 secured at its periphery between gaskets 15. An outlet tube or reed 16 has its inner end positioned against or in proximity to the central portion of said diaphragm and extends outwardly in threaded engagement with the correspondingly threaded inner surface of the cylinder 11.

Said reed beyond the cylinder 11 is provided with a reduced cylindrical flange 17, 15 extending axially beyond a shoulder 18. A sleeve 19 is normally positioned within the flange 17 and is itself provided with a radial flange 20, in slidable engagement with which latter is the flanged portion 21 of an internally threaded coupling member 22, which is adapted to be screwed upon the freely extending externally threaded end portion of said reed.

Horns of various shapes and sizes are provided such for instance as the short relatively high pitched horn 23, the longer and lower pitched horn 24, both of which are preferably rectilinear and are directed rearwardly along the opposite sides of the smoke stack of the locomotive shown in Fig. 1, and other short and long horns 25 and 26 extending forwardly and thence laterally downwardly so as to direct their respective notes likewise forwardly and laterally and at the same time prevent the entrance of rain, sleet, snow, and dirt into their freely extending open end portions.

The smaller end 27 of each horn (see Fig. 5) extends inwardly through the sleeve 19 and is provided with an outwardly flared flange 28 which partly encircles the rear end of said sleeve and is adapted to be firmly secured between said sleeve and the shoulder 18 of the reed, in addition to this smaller end 45 of the horn being brazed, soldered, or welded to the surrounding sleeve 19.

As shown in Figs. 2, 3 and 4, the fluid inlet member 12 of Fig. 5 may in reality, comprise a reduction L, each adjacent pair of such L's being connected together by pipes 29, separated by a T 30, into which leads a reduction L 31. When there are more than two sound-producing elements such as are here shown, the several pairs are connected as thus described and their respective reducing L's 31 are in turn connected together by pipes 32, extending outwardly from a suitable reducing T 33, which in turn is connected through a valve 34 of any well-known design and actuated by a lever 35 and cord 36 with a source of fluid pressure (not shown) such for instance as an air pressure tank of the kind used in well-known air brake systems.

From the drawings, it will be observed 65 that when necessary to replace, repair, or ad-

just any one or more of the horns or their corresponding sound-producing elements, the present structure provides a method by which the entire group of horns and elements together with their connecting piping and fluid-control valve can be removed from the supporting brackets as a unit. The several sound-producing elements are preferably of the same construction and size, the different musical notes being defined and controlled 75 by the size and shape of the respective horns which, while adapted to be positioned in any desired direction with respect to the vehicle, have been found to insure a most desirable result when positioned as shown.

Furthermore, it is to be noted that each of the sound-producing elements instead of being supported upon an arm of a bracket or yoke, comprising a plurality of such arms, may if desired be supported upon a bracket 85 connected directly to the flange 3 of the angle iron base independently of any of the other of said elements. Still again, it should be noted definitely that the distance from the source of fluid supply as represented by the pipe in which the control valve is situated through the respective branch pipes 32 and sub-branch pipes 29 into the respective casings 11 is equal in all cases so as to insure absolutely simultaneous and coincident operation of all of said elements.

And still further, while not limiting the invention in any way to the exact diameters of the pipes and connections illustrated, such a relationship may be present as for illustration, a $1\frac{1}{2}$ inch pipe at 34, $\frac{3}{8}$ inch pipes at 32, $\frac{1}{4}$ inch pipes at 29, the latter connecting with the interior of the respective casing through a restricted inlet port of as little as $3/32$ or even $1/16$ inches which may be used toward the end of reducing the extremely high pressure in the air or similar supply to as low a pressure as approximately 60 pounds per square inch within the respective sound-producing elements.

Having thus described my invention, what I claim and desire to protect by Letters Patent of the United States is:—

1. A signal adapted for vehicles and comprising a plurality of fluid-actuated sound-producing elements, sound amplifying means for each of said elements, one of said means being adapted to be directed towards the rear of a vehicle while the other means are directed towards angularly different positions, and power supply means connecting the several elements together and to a common source, said supply means comprising a common supply pipe, a reducing connection leading into a plurality of branch pipes, a second reducing connection leading from each branch into secondary branch pipes, and a reducing connection leading from each of said secondary branches into the respective elements.

2. A signal comprising a plurality of fluid-actuated elements, pipes connecting pairs of said elements, pipes connecting pairs of said first pipes to a common source of fluid pressure, and means to control the application of pressure through said pipes to said elements simultaneously.

3. A signal adapted for vehicles and comprising a plurality of fluid-actuated sound-producing elements, each of which comprises a casing having a restricted inlet, tubular means adapted to connect with a source of relatively high fluid pressure, and tubular means connected to said first tubular means through a reducing connection, each of said last-named means leading through a second reducing connection into a third set of branch tubular means, said last-named tubular means leading into the respective casings of a pair of said elements through said restricted inlets, and the fluid pressure from an extraneous source reducing step by step after passing each reducing connection and again upon entering each of said casings.

4. A signal adapted for vehicles and comprising a plurality of casings forming portions of respective fluid-actuated sound-producing elements, each of said casings having a restricted inlet, a pipe adapted to convey fluid pressure from an extraneous source and of a given cross sectional area, branch pipes together having a total cross sectional area greater than the area of said first pipe and respectively of less diameter than first pipe, and a second set of branch pipes connected with each of said first branches and being respectively of less diameter than the diameter of said branch and together totalling a greater cross sectional area than that of said branch, and each of said last-named branch pipes leading through said restricted inlet into the casing of a corresponding sound-producing element.

5. A signal adapted for vehicles and com-

prising a plurality of fluid-actuated sound-producing elements, sound amplifying means for each of said elements, one of said means being adapted to be directed towards the rear of a vehicle while the other means are directed towards angularly different positions, and power supply means connecting the several elements together and to a common source, said supply means comprising a common supply pipe and reducing connections to operatively connect each of said elements to said supply pipe.

6. A signal comprising a plurality of fluid-actuated elements, pipes connecting pairs of said elements, pipes connecting pairs of said first pipes to a common source of fluid pressure, and means to control the application of pressure through said pipes to said elements simultaneously, the connections between the source of pressure and the said elements including a reduction in their cross sectional area.

7. A signal comprising a plurality of fluid-actuated elements, pipes connecting pairs of said element, pipes connecting pairs of said first pipes to a common lead line from a source of fluid pressure, and means to control the application of pressure through said pipes to said elements simultaneously, the fluid inlet of each of said elements being of less area than the cross section of said lead line.

8. A signal comprising a plurality of fluid-actuated elements, pipes connecting pairs of said element, pipes connecting pairs of said first pipes to a common lead line from a source of fluid pressure, and means to control the application of pressure through said pipes to said elements simultaneously, the combined areas of the fluid inlets of said elements being less than the cross sectional area of said lead line.

In testimony whereof I have affixed my signature.

CLARK COOPER.
